UNITED STATES PATENT OFFICE.

ROY RITTENHOUSE, OF WORMLEYSBURG, PENNSYLVANIA.

COMBINED CAR AND TRAIN-PIPE COUPLING.

No. 927,600.

Specification of Letters Patent.

Patented July 13, 1909.

Application filed May 2, 1908. Serial No. 430,511.

To all whom it may concern:

Be it known that I, ROY RITTENHOUSE, a citizen of the United States of America, residing at Wormleysburg, in the county of Cumberland and State of Pennsylvania, have invented certain new and useful Improvements in a Combined Car and Train-Pipe Coupling, of which the following is a specification.

10 This invention relates to car couplers designed for use in operating the train pipe connection and train pipe couplers.

An object of this invention is to provide novel means for uncoupling the car and simultaneously disconnecting the flexible pipes of the air brake supply and the invention also contemplates the provision of means for operating a valve of the train pipe of the air brake system.

20 With the foregoing and other objects in view, the invention consists in the details of construction and in the arrangement and combination of parts to be hereinafter more fully set forth and claimed.

25 In describing the invention in detail, reference will be had to the accompanying drawings forming part of this specification wherein like characters denote corresponding parts in the several views, in which—

30 Figure 1, is a view in perspective of the front end of a car with the invention applied thereto; Fig. 2, is an end view of a bracket in which the operating shaft is mounted; Fig. 3, is a detail view of a bell crank lever; Fig. 4, is a detail view of the valve operating wrench. Fig. 5, is a perspective view showing the application of a modified arrangement for operating the air pipe valve in conjunction with a shaft.

35 In these drawings A, denotes a car frame; B a draw-bar mounted thereon; C, a draw-head preferably of the Janney type at the end of the draw-bar. The knuckle c, of the draw-bar has its tail-piece held by the pin D, when the cars are coupled and said pin D, has a flexible connection d shown in the form of a chain, leading to an arm E, which arm E, is mounted on the shaft F, and partial rotation of the shaft F, will result in elevating or 40 lowering the arm E, thus raising the pin from the draw head or allowing it to be returned to operative position with relation to the tail-piece of the knuckle c.

The shaft F, is partially rotatable in the bearing f, but that portion of the shaft intermediate the ends which are mounted in the

bearings is angular in cross section in order that the arm E, and another arm G, may be applied thereto and take motion therefrom.

The arm G, has a link g, on its end connected to one member H, of a bell crank lever I, and the member h, of the bell crank lever is provided with a yoke J, forming a seat for the hose or flexible end K, of the train pipe. The yoke J, is provided with a shank j, fitted 65 in an aperture of the member h, of the bell crank lever and said shank is retained in place by the cotter pin j'.

The train pipe L, has a valve with a valve stem M, but said valve stem is engaged by 70 the wrench N, which wrench is journaled in the bearing n, applied to the frame of the car. The upper end of the wrench is provided with a toothed segment O, and the said toothed segment engages the teeth of the rack P, 75 which rack is applied to the operating shaft F. The shaft F, is mounted to partially rotate and reciprocate in its bearing and the reciprocal motion of said shaft when the rack P, is in engagement with the toothed segment 80 will result in partial turning of the wrench N, and consequently partially rotating the valve stem. It is through the manipulation of the shaft F, that the air supply is controlled 85 through the medium of the valve.

In operation, assuming that the cars are coupled and the air pipes are connected, movement of the shaft longitudinally of its axis would result in partial rotation of the train pipe valve which movement is sufficient 90 to close the valve. Partial rotation of the shaft F, would then result in elevating the coupling of the train pipe so that it would be disconnected from a section of the coupler on the opposite car. At the same time, movement would be communicated to the pin D, through the arm E, and the flexible connection d, and the coupler would be free to open 95 as the cars moved apart. A reverse movement of the parts just described will result in 100 returning the pin to its operative position in the draw-head and the train pipe coupling would descend to be engaged by the coupling member on the other car. The bracket Q, is applied to the frame of the car and is designed 105 to support the central portion of the shaft F. The said bracket does not completely embrace the shaft but is open at the top so that the angular portion of the shaft F, will freely rotate therein. The bracket has cut-away 110 portions q, to receive the inner ends of the arms E and B.

In the modification shown in Fig. 5, A' indicates the car frame, f', a bearing, and F', a shaft which parts are similar in all respects to the car frame A, bearing f, and shaft F, heretofore described. In this modification the rack P, is omitted and a hook 1, is applied to the shaft F', said hook engaging a lever 2, which lever is pivoted to a bracket 3, attached to the car frame. The lower end of the lever extends through a slot 5, in the crank 4, which crank is mounted on the stem 6, of the valve applied to the train pipe L', which train pipe has the usual flexible coupling K'.

15 I claim—

1. A coupler and train pipe operating mechanism comprising a shaft, arms thereon, a toothed rack on the shaft, a toothed segment engaged by the rack, a train pipe valve operating device actuated by the toothed segment, a train pipe coupler, a car coupler, and means for controlling the train pipe coupler and car coupler at a single operation.

2. In a car and train pipe coupler, a train pipe having a valve, means for operating the valve, a toothed segment on the valve operating means, a shaft, means on the shaft for engaging the toothed segment to partially rotate it, means for supporting the train pipe coupling and means for controlling said support.

3. In a car and train pipe coupler, a shaft on the frame of the car, an arm extending therefrom, a bell crank lever mounted in bearings on the frame of the car, a link connecting the arm and one member of the bell crank lever, and means on the other member of the bell crank lever for engaging a train pipe coupler.

4. In a car and train pipe coupler, a shaft journaled on the frame of the car, a bell crank lever, means on one member of the bell crank lever for supporting the train pipe coupling, and means for connecting the opposite member of the bell crank lever with the shaft whereby partial rotation of the shaft

results in the oscillation of the bell crank lever.

5. In a car and train pipe coupler, the combination with the air supply pipe, of an air brake system, a valve in the pipe, means for opening and closing the valve, a toothed segment on the means for opening and closing the valve, a toothed rack engaging the segment, a shaft on which the toothed rack is mounted, and means for mounting the shaft to permit reciprocation thereof.

6. In a car and train pipe coupler, the combination with an air supply pipe, of an air brake system, a valve in the pipe, a shaft mounted to slide transversely of a car, a lever operated by the shaft, a valve in the train pipe, and means whereby the movement of the lever operates the valve.

7. In a car and train pipe coupler, a train pipe having a rotating valve and a coupler mounted on the car, a shaft, and means connecting the shaft to the valve and the coupler whereby a rotating and sliding movement of the shaft will simultaneously operate the valve and coupler mechanism.

8. The combination with a car, of a car coupler carried thereby, means connected to the coupler to uncouple the car, a hose extending from the car having a coupling head which will uncouple when raised, and means connecting the free end of the hose to the uncoupling means to raise the head.

9. The combination with a car provided with a car coupler of the Janney type, an air hose having a coupling head of the Westinghouse type, and means connected to the car coupler and the air hose adapted to operate the coupler and the air hose to uncouple them substantially simultaneously.

In testimony whereof I affix my signature in the presence of two witnesses this 30th day of April, 1908.

ROY RITTENHOUSE.
